DESIGN FOR A PIANO ACCORDION

Robert D. Budlong, Chicago, Ill., assignor to Chicago Musical Instrument Company, Chicago, Ill., a corporation of Illinois

Application September 28, 1936, Serial No. 65,035

Term of patent 7 years

To all whom it may concern:

Be it known that I, Robert D. Budlong, a citizen of the United States, residing at Chicago, in the county of Cook and State of Illinois, have invented a new, original, and ornamental Design for a Piano Accordion, of which the following is a specification, reference being had to the accompanying drawing, forming part thereof.

In the drawing:

Fig. 1 is a front elevation of a piano accordion showing my new design.

Fig. 2 is an elevational view of one side of the same.

Fig. 3 is an elevational view of the other side of the accordion.

I claim:

The ornamental design for a piano accordion as shown.

ROBERT D. BUDLONG.
